(57) **CLAIM**

The ornamental design for a connector sleeve with cutout, as shown and described.

DESCRIPTION

FIG. 1 is a front, top, left-side view of the connector sleeve with cutout;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof; and,

FIG. 7 is a bottom plan view thereof.

The Dash-Dash broken lines depict portions of the connector sleeve with cutout and form no part of the claimed design. The Dash-Dot broken lines depict the bounds of the claimed design and form no part thereof.

1 Claim, 7 Drawing Sheets
